UNITED STATES PATENT OFFICE.

JACOB C. HEIM, OF PHILADELPHIA, PENNSYLVANIA, ASSIGNOR TO BROWN & BAILEY COMPANY, OF PHILADELPHIA, PENNSYLVANIA, A CORPORATION OF PENNSYLVANIA.

KNOCKDOWN BOX.

1,400,060.

Specification of Letters Patent. Patented Dec. 13, 1921.

Application filed February 24, 1920. Serial No. 360,632.

To all whom it may concern:

Be it known that I, JACOB C. HEIM, a citizen of the United States, residing in the city of Philadelphia, county of Philadelphia, and State of Pennsylvania, have invented certain Improvements in Knockdown Boxes, of which the following is a specification.

This invention relates especially to collapsible boxes made from paper boards cut or die to forms that can be erected to provide coating tops and bottoms respectively formed from a single sheet.

The present improvements are designed to provide a box from sheets having parts adapted to be erected and joined so as to provide a structure that is symmetrically reinforced in all of its sides or sides and ends without waste of material, while having a neat and finished interior construction with the ends of locking members covered and tied in place.

My improved box provides the desiderata of a closed construction in which each of the four sides has triple thickness, affording stiffening reinforcements for the respective sides, and a smooth and slight interior construction extending substantially throughout lengths of all the sides or sides and ends, adapted to be erected from unitary blanks conveniently and locked together securely.

In the accompanying drawings, Figure 1 is a plan view of one of the formed and knocked-down sheets used in making a closed box in accordance with my invention; Fig. 2 is a plan view of the other of the two knocked-down sheets which may be used in forming the complementary box member; Fig. 3 is a perspective view of a box member erected from the construction shown in Fig. 1; Fig. 4 is a perspective view of a box member erected from the construction shown in Fig. 2; Fig. 5 is a sectional view taken on the line 5^x—5^x of Fig. 3; Fig. 6 is a perspective view of a section of a box member of modified construction; Fig. 7 is a broken sectional view taken on the line 7^x—7^x of Fig. 6; Fig. 8 is a perspective view of a section of a further modified construction; Fig. 9 is a broken sectional view taken on the line 9^x—9^x of Fig. 8; Fig. 10 is a perspective view of a box section embodying a further modification in construction; and Fig. 11 is a broken sectional view taken on the line 11^x—11^x of Fig. 10.

The construction illustrated in Fig. 1, which is adapted to be erected to form the box member illustrated in Figs. 3 and 5, comprises the rectangular body section 1 having the side sections 2 integrally connected therewith along the scores 3, and the end sections 4 integrally connected therewith along the scores 5. The ends 4 have the flaps 6 integrally connected therewith along the scores 7. The sides 2 have the end extensions 8 integrally connected therewith along the scores 9 in line with the scores 5 and separated from the parts 4 and 6 by through cuts 10 in line with the scores 3. The flaps 6 are approximately of the same length and the same width or depth as the sections 4. The flaps or extensions 8 are of substantially the same depth or width as the respective parts 2, 4 and 6, and of a length corresponding to the combined widths of the parts 4 and 6 so that the sheet may be formed without substantial waste. Each of the extensions 8 is provided with a slot 11 preferably parallel to and near its inner edge, and each of the flaps 6 is provided with the lugs 12 preferably near its respective outer ends and adapted to be engaged in the corresponding slots 11.

The structure illustrated in Fig. 2, which is adapted to be erected to form the box member illustrated in Fig. 4, comprises the rectangular body section 1' (similar to the section 1) having the integrally connected end sections 2' joined thereto along the scores 3' and the integrally connected side sections 4' joined thereto along the scores 5'. The side sections 4' are provided with the integrally formed flaps 6' of substantially the same width or depth and joined thereto along the scores 7' parallel to the scores 5'. The end sections 2' are provided with the integrally formed extensions 8', having substantially the same depth or width, joined thereto along the scores 9' in line with the scores 5', and separated from the sections 4' and 6' by the through cuts 10' in line with the scores 3'. The parts 2' are provided with the slots 11' preferably parallel to and near the lines 10' and the flaps 6' have thereon near the ends thereof the lugs or ears 12' adapted to be engaged in the slots 11'. It will be observed that this sheet can be formed substantially without waste.

The box members formed from these blanks are adapted to be combined in tele-

scoping relation to form a closed construction having each of its four sides or sides and ends provided with triple thickness, with the additional thickness provided 5 at the corners by the ends 8 and 8' extending oppositely therefrom respectively, these ends or extensions being covered and held in place by the respective flaps 6 and 6' which extend in opposite directions from 10 the respective corners and to or the greater part of the distance to the respective parts 1 and 1'.

As illustrated in Figs. 6 and 7, the flaps 6^a are of such depth that they are adapted 15 to be engaged and locked in the scores 5^a of the body part 1^a, so that such flaps are not only held in place but hold in place the locking extensions 8^a of the parts 2^a and provide a strut or reinforcing compression 20 member joined to the outer members 2^a with the provision of strength as well as a firmly assembled construction. Preferably the flaps 6^a are made of a depth that will cause them to be sprung or bowed inwardly with 25 the provision of additional means resisting lateral bending of the sides.

As illustrated in Figs. 8 and 9, the flaps 6^b are each provided with one or more lugs 6^c adapted to be sprung into the scores 5^b 30 joining the body member 1^b to the outer

member 2^b with the provision of means for locking the parts 6^b in place and thus holding in place the locking and extensions 8^b of the parts 2^b, the parts 6^b being slightly bowed inwardly with provision of additional 35 resistance to lateral bending of the sides.

As illustrated in Figs. 10 and 11, the parts 6^d are provided with ears or lugs 6^e which extend through slots 5^d in the body section 1^c, thus locking in place as well as covering 40 the ends of the inturned side extensions 8^c on the members 2^c.

Having described my invention, I claim:

A knock-down box member having a rectangular body section provided with parallel 45 edge scores, side sections hinged to said body section along said scores; flaps hinged to said side sections and adapted to be engaged in said scores in bowed relation to said side sections; side sections hinged to said body section along lines at right angles to said scores, and extensions hinged to the ends of said side sections second named and adapted to be engaged between said flaps and side sections first named. 50

In testimony whereof I have hereunto set my name this 20th day of February, 1920.

JACOB C. HEIM.
